DESIGN FOR A TEXTILE FABRIC

Samuel Kornfeld, New York, N. Y.

Application February 20, 1940, Serial No. 90,370

Term of patent 3½ years

To all whom it may concern:

Be it known that I, Samuel Kornfeld, a citizen of the United States, residing in New York city, in the county of New York and State of New York, have invented a new, original, and ornamental Design for a Textile Fabric, of which the following is a specification, reference being had to the accompanying drawing, forming part thereof.

The figure is a plan view of a textile fabric showing my design.

The design unit is contained between the dot and dash lines, which unit is repeated in regular succession as indicated by the extension beyond the unit boundaries.

I claim:

The ornamental design for a textile fabric, substantially as shown and described.

SAMUEL KORNFELD.
